UNITED STATES PATENT OFFICE

105,816

DESIGN FOR AN AIR CONDITIONING COOLER CABINET

Wayne T. Swingle, Hastings, Nebr.

Application July 14, 1937, Serial No. 70,430

Term of patent 7 years

To all whom it may concern:

Be it known that I, Wayne T. Swingle, a citizen of the United States, residing at Hastings, in the county of Adams and State of Nebraska, have invented a new, original, and ornamental Design for an Air Conditioning Cooler Cabinet, of which the following is a specification, reference being had to the accompanying drawing forming part thereof.

Figure 1 is a front perspective view of an air

conditioning cooler cabinet showing my new design; and Figure 2 is a rear perspective view thereof.

The essential features of my design reside in the portions shown in full lines.

I claim:

The ornamental design for an air conditioning cooler cabinet as shown and described.

WAYNE T. SWINGLE.
